UNITED STATES PATENT OFFICE

PAUL KOBLER, OF LYNBROOK, NEW YORK

BOOK PAGE HOLDER

Application filed December 22, 1931. Serial No. 582,544.

This invention relates to improvements in page holding devices for bookholders. The bookpageholder according to the present invention comprises bookpageholding means which are approximately in the same elevation as the middle of the upfolded book is, a lever on each side of the book or under the book, these levers being movable having at their ends short parts which are holding the upfolded sheets in position, further means to connect the two levers so that they can work simultaneously.

10 A constructional example of the bookpageholder according to the present invention is illustrated on the accompanying drawing, in which:

Fig. I is a plan view of the device and

Fig. II is a three-dimension figure showing the same device holding the upfolded pages 20 of a book.

Referring now to the drawing 1 denotes the supporting plate for the right hand lever and 2 the supporting plate of the left hand lever. These plates 1 and 2, as shown in Fig. II 25 may be secured to the top surface of a support indicated in broken lines, so that the device holds a book in the position shown, and so that part of the book may hang down over the front face of said support, and be engaged by two hooks, 9, 9 projecting from said front face. The two levers are connected by rod 3 and 4, 4 indicate short projections 30 laterally from each lever which are holding the upfolded pages from falling down. 5 is the left hand, 6 the right hand lever.

When lever 5 is displaced in the direction towards the other lever 6, lever 6 makes the same movement towards the middle of the

book. By moving lever 5 outwards again, lever 6 is moved outwards, or away from the book too. Lever 5 has its pivotal point between the ends while lever 6 has its pivotal point on one end. 7 shows pivotal point of lever 5, 8 shows pivotal point of lever 6.

When the levers are open the pages of the book may be folded upwards and when it is desired to keep them in position the levers are closed.

I claim:

1. A page holding device comprising supporting means, a pair of spaced opposed levers each having at one end a lateral extension projecting toward the other lever so spaced from the support and the levers so pivoted that said projections may overlie and play parallel to the leaves of a book resting on said support and means so connecting said levers, that when one lever is moved the other moves in the opposite direction to engage over or disengage from said leaves.

2. A page holding device comprising a pair of bars upon which a book may rest, a pair of levers each pivoted to a bar at opposite sides of the place intended to be occupied by the book to play parallel to said bars each lever being so extended and provided with a projection toward the other lever that such projections may overtie the pages of the book and means connecting the levers on opposite sides of their pivots respectively so that movement of one lever to carry its projection over or away from a page will cause the other lever to do the same by a movement in the other direction.

PAUL KOBLER.
